UNITED STATES PATENT OFFICE.

FRIEDERICH SCHLATTER, OF MADRETSCH, SWITZERLAND.

MICROMETER-GAGE.

SPECIFICATION forming part of Letters Patent No. 407,903, dated July 30, 1889.

Application filed February 19, 1889. Serial No. 300,498. (No model.) Patented in Switzerland December 31, 1888, No. 303.

To all whom it may concern:

Be it known that I, FRIEDERICH SCHLATTER, a citizen of the Republic of Switzerland, residing at Madretsch, in the Republic of Switzerland, have invented certain new and useful Improvements in Micrometrical Measuring-Instruments, (for which I have obtained Letters Patent in Switzerland, No. 303, dated December 31, 1888,) of which the following is 5 a specification.

This invention relates to improvements in that class of measuring-instruments that are used for measuring very small dimensions, such as the thickness of paper, fabrics, sheet 10 metal, wire, &c.

The object of my invention is to provide a measuring-instrument of this kind which permits of reading off the dimensions of the article at any desired time after the measurement has been taken.

The invention consists in the construction and combination of parts and details, as will be fully described and set forth hereinafter, and finally pointed out in the claims.

25 In the accompanying drawings, Figure 1 is a face view of my improved measuring-instrument. Fig. 2 is a vertical longitudinal sectional view of the same on the line $x-x$, Fig. 3. Fig. 3 is a vertical transverse sectional view of the same on the line $y-y$, Fig. 2. Fig. 4 is an elevation of the upper half portion of the instrument, the pointer being provided with a nonius. Fig. 5 is an enlarged detail face view of the fingered arm. Fig. 6 is 30 a side view of the same.

Similar letters of reference indicate corresponding parts.

The casing A, which is provided at its lower end with a recess C^2 in one side edge, contains 40 the slide B, provided with the abutting surface B' , which is opposite the other abutting surface formed by the end of a screw C' , which is adjustable in the bottom arm C^3 of the casing A, and can be locked in place by means of a suitable nut P. The slide B is provided on its upper end with a head A. In the casing 45 an arbor L is journaled, on which is mounted a pinion K, that engages a rack b' , formed on one edge of a longitudinal slot b in the slide B. On the outer end of the arbor L an arm H is fixed and adapted to rotate over a dial

E, fixed on the front of the casing and provided with a circular graduated scale. To the free end of the arm H the finger n is pivoted, which is provided at its hinged end with 55 the two shoulders or stops n^2 or n^3 , that can rest against the pin n' on the arm H. A spring i, secured to the arm H and bearing against a pin i' of the finger n, keeps said finger in line with the arm H and the stop n^2 60 against the pin n' , as shown in Fig. 5. A pointer G is mounted on a hub J on the arbor L, and said pointer G is provided with a projecting-pin g, on which the finger n of the arm H can act.

The glass R over the dial is held in a ring D, mounted to rotate on the plate F, on which the dial E is held, and said ring D is provided with the pin Q, which is to be used for adjusting the apparatus for controlling cer- 70 tain measurements.

The slide B is provided with a longitudinal slot B^2 , containing the spiral spring M, of which one end bears against the pin N, projecting from the case C into said slot and the 75 other end bears against the upper end of the slot B^2 , thus pressing the slide B upward. If desired, the pointer or hand G may be provided with a nonius W for very accurate measurements.

80 The operation is as follows: When the abutting surfaces B' and C' are as far apart as possible, the hand or pointer G is at O, and when the said abutting surfaces are brought in contact the hand or pointer G will have 85 made one revolution from right to left, and will again be at O. The article to be measured is placed upon the abutting surface C' and the slide B pressed down until the surface B' rests upon the said article. By pressing down the slide B the arm H is rotated from right to left, and its finger n strikes against the pin g on the pointer or hand G, and also turns the same from right to left. If the object is very small, the slide B can be 90 depressed farther than if the object is larger, and thus for a small object the hand or pointer G will be moved farther to the left than for a larger object. As the graduated scale is subdivided from left to right, it follows that as 100 the hand G rotates from right to left it gradually passes over the lower numerals of the

scale. When the slide B is released, the spring M throws it upward and brings the arm H back to its initial position, the hand G remaining in the position in which it indicates the dimension of the article measured. Measurements can thus be taken with the above-described instrument in the dark and the measurements read off when the instrument is brought into light, as the hand G retains its position.

To bring the hand G back to O on the dial-scale, the slide B is pushed down until the surfaces B' and C' are in contact, the object having been removed. Thereby the arm H is caused to make one complete revolution from right to left, and in so doing carries the hand G around to O. If the slide B is now released, the spring M throws it upward and the arm H is caused to make a complete revolution from left to right. In so doing the end of the finger n swings to the left, where it strikes against the pin g and passes under said pin, the spring i bringing said finger into the normal position as soon as the pin g has been passed.

Having thus described my invention, I claim as new and desire to secure by Letters Patent—

1. In a measuring-instrument, the combination of a casing provided with a dial, a slide in said casing provided with a rack, an arbor in said casing provided with a pinion which is engaged by said rack, an arm fixed on said arbor, a hand mounted on said arbor over the dial and provided with a pin which is engaged

by said arm, and a spring disposed in a slot in said slide and connected at one end to said casing, substantially as described.

2. In a measuring-instrument, the combination, with a casing and a slide in the same, of a dial on the casing, an arbor in the casing, which arbor is rotated by the slide, an arm fixed on said arbor and provided with a swinging spring-finger, a hand mounted to swing over the dial and provided with a pin on which the spring-finger of the arm can act, and a spring abutting against a fixed point of the casing and pressing the slide upward, substantially as set forth.

3. In a measuring-instrument, the combination of the casing B and the slide C, having the slots B² and b, the latter having the rack b formed on one edge, the arbor L, the pinion K on the same engaging the rack b', the spring M in the slot B², the dial E on the casing, the arm H on the arbor L, the finger n, pivoted on said arm, the spring i, secured to the arm H, acting on the finger n, and the hand G, mounted to rotate over the dial and provided with the pin g, on which the finger n can act, substantially as set forth.

In testimony that I claim the foregoing as my invention I have signed my name in presence of two subscribing witnesses.

FRIEDERICH SCHLATTER.
